OF D 17,740

DESIGN.

O. GERMER.

HEATING STOVE.

No. 17,740.

Patented Sept. 27, 1887.

UNITED STATES PATENT OFFICE.

OTTO GERMER, OF ERIE, PENNSYLVANIA, ASSIGNOR TO BLACK & GERMER,
OF SAME PLACE.

DESIGN FOR A HEATING-STOVE.

SPECIFICATION forming part of Design No. 17,740, dated September 27, 1887.

Application filed August 22, 1887. Serial No. 247,616. Term of patent 3½ years.

To all whom it may concern:

Be it known that I, OTTO GERMER, a citizen of the United States, residing at Erie, in the county of Erie and State of Pennsylvania, have 5 invented and produced a certain new and original Design for Heating-Stoves; and I do hereby declare the following to be a full, clear, and exact description of the invention, such as will enable others skilled in the art to which it appertains to make and use the same, reference being had to the accompanying photograph, and to the letters of reference marked thereon, forming part of this specification.

My design relates particularly to the form 15 and ornamentation of heating-stoves; and it consists in the features hereinafter set forth and described, and illustrated in the accompanying photograph, showing a perspective view of a heating-stove embodying the same. 20 In its general shape the stove is rectangular, with the open front thereof surmounted with an arched and outwardly-projecting hood, above which is an ornamental panel, the whole being surmounted by the overhanging molding of the top of the stove.

The base of the stove, A, is in its general shape rectangular, the top thereof, B, being substantially flat, forming a hearth for the stove. Each of the front corners of this hearth 30 is an ornamental panel, D, of scroll-work, and across the front of the hearth, between the panels D D, are ornamental tiles or panels E. The outer edge of the hearth B is finished with a plain ogee-band, F, below which is a serrated band, G. Below the band G, I secure to the base A a curtain, H, ornamented with shell-work H', which curtain H joins with the legs I of the stove, the band of shell-work H' being continued on the upper portion of the 40 legs I, so as to form a continuous band around the base of the stove.

Above the top of the base A is an ornamental rod, J, which extends outward from each corner of the upright portion of the stove 45 and around the ends and front of the hearth B. This rod J is ornamented with scroll-work at its ends, corners and across the front thereof.

The ends K of the upright portion of the 50 stove are ornamented with rectangular panels L L, the styles K' of which are ornamented with

single lines k and corner ornaments, k', surrounding the panels L. The panels L are ornamented by central figure, L', and corner figures, L'', of raised filigree-work, and also by 55 rosettes L''' in the corners and at the centers of the sides thereof.

The front corners of the upright portion of the stove consist of posts M, having front panels, N, the lower portion of the front panels 60 thereof being ornamented with a single column of spiral molding, O, the styles of the panels being plain ogee moldings P. The upper portions of the fronts of the corner-posts M are ornamented with foliated panels Q, sur- 65 mounted by human busts R.

Between the corner-posts M on the front of the stove, above the hearth B, is a movable paneled plate, S, adapted to close up the space between the hearth B and the lower part of the 70 grate T, the panel in the plate S being occupied by words in ornamental letters, the same substantially occupying the whole of the panel S' in the plate S.

The upper portion of the front of the stove 75 between the foliate panels Q consists of an outwardly-projecting arched hood, a, the lower edge, b, thereof being rounded, above which the top of the hood a is ornamented with small panel-work c. Above the arch of the hood a 80 and opposite the top of the panels Q a band-molding, d, extends across the front of the stove, and the panel a', formed by the arched hood a and the styles of the foliate panels Q and the band-molding d, is ornamented with 85 griffin-heads d' near the ends thereof, in bas-relief and foliate work meeting in scrolls over the central part of the arched hood a. Above the molding d a panel, f, is formed by the band-mold d, the busts R, and the fascia e, 90 which panel is provided with a central ornamental face, g, in bas-relief, from which face foliate work extends each way and surrounds medallions i in the panel f, these medallions i being either of tile inserted in spaces left in 95 the panel for that purpose or made a part thereof, if desired. The fascia e of the top of the stove is ornamented with foliate work j. The general contour of the top l of the stove is pyramidal, the sides and ends curving 100 gradually to the apex thereof, which is surrounded by an ornamental vase or figure, m,

the ornamentation of the top *l* consisting of, first, a plain band-cornice, *n*, overhanging the fascia *e*; second, of a band of shell-work-ornamented molding, *o*, curving inward and upward; third, of a plain molded band, *p*; fourth, of a serrated band, *r*; fifth, of a plain band, *s*; sixth, of a serrated band, *t*, and, seventh, of panels *u*, ornamented with raised scroll-work, which panels extend to the apex of the top *l*, thus completing the top of the stove to the base of the ornamental figure *m*, hereinbefore referred to.

Having thus fully described my design, what I claim as new, and desire to secure by Letters Patent of the United States, is—

1. In a design for an open-front heating-stove, the base *A*, consisting of the ornamental hearth *B*, having central front panels, *E*, ornamented with tiles, and corner panels, *D*, ornamented with scroll-work, substantially as shown and described, and the curtain *H*, having shell ornaments *H'* thereon, substantially as shown and described.

2. In a design for the ends of an open-front heating-stove, the styles *K'* and the sunken panels *L*, having central and corner ornamentation, substantially as shown and described.

3. In a design for an open-front heating-stove, the corner-posts *M*, ornamented with

spiral molding and foliate panels, with the projecting arched hood *a*, with a rounded edge and ornamented with panel-work, the panel *a'*, ornamented with griffins and foliate work, the band-mold *d*, and the panel *f*, ornamented with medallions and foliate work, substantially as shown and described.

4. In a design for an open-front heating-stove, the top *l*, ornamented with plain shell-work and serrated band-molds and ornamental panels, substantially as shown and described.

5. In a design for an open-front heating-stove, the base *A*, ornamented substantially as shown and described, with the ends of the upright portion thereof having panels *L* therein, ornamented substantially as shown and described, the front posts, *M*, ornamented substantially as shown and described, and the arched hood *a* and the panels *a'* and *f*, ornamented substantially as shown and described, and the top *l*, ornamented substantially as shown and described.

In testimony whereof I affix my signature in presence of two witnesses.

OTTO GERMER.
